PROCESS FOR PRODUCING ALIPHATIC ESTERS

Maurice Mention and Pierre Godet, Melle, Deux-Sèvres, France, assignors to Les Usines de Melle (Societe Anonyme), Saint-Léger-les-Melle, France, a corporation of France

Application May 18, 1953, Serial No. 355,724
Claims priority, application France December 5, 1952

6 Claims. (Cl. 260—410.9)

This invention relates to a process for making aliphatic esters, particularly by reaction of propylene with acetic or other aliphatic acid in the presence of a strong mineral acid.

It is known that acetic acid can react with propylene in the presence of sulfuric acid. Many modes of carrying out such reaction have been described, to produce a mixture comprising sulfuric acid, mono-isopropyl sulfate, acetic acid and isopropyl acetate, but containing in addition propylene polymers and decomposition products.

Such processes have been carried out in batches, each batch (containing a mixture of acetic and sulfuric acids) being treated with propylene until the latter is no longer absorbed.

The reaction mixture obtained is then treated for recovery therefrom of the ester formed, the treatment generally consisting in diluting the mixture with water to isolate a mixture of acid, ester and water by decantation and/or distillation, the acid-ester-water mixture being then separated into its components by known means. The recovered sulfuric acid, thus, is in dilute form and must be concentrated before reuse.

A process of the batch type has been proposed which involves the production of the ester in a reactor, removal of the reacted mixture and distillation of same by bubbling an olefine therethrough to remove some of the ester. Thereafter the remainder of the mixture is returned to the reactor for further processing.

The principal object of the present invention accordingly is to produce a simple and efficient process for the production of aliphatic esters which shall overcome in part at least some of the disadvantages of the prior processes.

The invention accordingly comprises the novel processes and steps of processes, specific embodiments of which are described hereinafter by way of example and in accordance with which we now prefer to practice the invention.

We have found in accordance with our invention that such isopropyl esters can be produced by continuously feeding propylene and saturated aliphatic acid having 2-8 carbon atoms into a bath maintained at about 60-80° C. The corresponding isopropyl ester is thereby produced. The bath at the equilibrium has approximately the following composition:

	Percent
Sulfuric acid	20-30
Aliphatic acid	5-30
Isopropyl ester	5-10
Water	0.5-10
Isopropyl hydrogen sulfate	69.5-20

The rate of feed of the aliphatic acid is maintained at a sufficient rate so that the aliphatic acid content of the bath is maintained in the range mentioned and the rate of feed of propylene is regulated at about 2-5 cubic meters per hour per kilogram of the bath. The isopropyl ester as it is formed is removed from the bath by the propylene-containing gas and may be separated readily therefrom, whereupon the propylene-containing gas may be circulated back to the system. Under such conditions

2

formation of propylene polymers is extremely low and it suffices continuously to replace only a very small proportion of the bath to maintain its activity. This may be done by continuously withdrawing a small proportion of the bath, the feed of reactants to the bath being so controlled that the volume of the bath remains constant.

In the following discussion preceding the examples the production of isopropyl acetate is explained. It is to be understood that these observations apply also to the production of other esters. The bath for the production of isopropyl acetate has the following composition:

	Percent
Sulfuric acid	20-30
Acetic acid	5-30
Isopropyl acetate	5-10
Water	0.5-10

the remainder being isopropyl hydrogen sulfate. The bath may be initially formed by any suitable means. In operation, the bath is fed with acetic acid and propylene under conditions hereinbelow set forth.

TEMPERATURE

The working temperature is maintained substantially constant at a value in the range 60-80° C. The preferred temperature is between 65° and 70° C. because at such temperatures polymer formation is very low while the bath is still capable of absorbing enough propylene. As a matter of fact, the absorption capacity per hour of the bath increases as temperature increases but polymer formation also increases as temperature increases.

ACETIC ACID FEED

Acetic acid is continuously fed to the bath at a rate such that the acetic acidity in the bath remains substantially constant at the chosen value. As stated above, the acetic acidity is in the range of 5-30%. However, the preferred range is 10-20% because below 10% the quickness of absorption of propylene is relatively low, whereas above 20% more acetic acid is carried off by the non-absorbed propylene, and, as a result, recovery of isopropyl acetate in a pure state is more costly.

PROPYLENE FEED

For maintaining in equilibrium the composition of the bath and removing the isopropyl acetate as it is formed, it is necessary that the gaseous feed rate be maintained between certain limits. The propylene feed rate to the bath should be of 2-5 cubic meters per hour per kg. of bath, preferably 2.5-4 cubic meters per hour per kg. of bath. Under such conditions the whole of the isopropyl acetate formed is carried off as vapors by the excess gas, together with a quantity of acetic acid and small amounts of isopropyl alcohol and isopropyl oxide. The resulting gaseous mixture is freed from the vapors it contains, preferably by cooling then, if need be, washing with acetic acid or another liquid capable of dissolving isopropyl acetate but from which isopropyl acetate can be readily separated, for example through distillation. The gas freed from the products carried off is recycled to the reaction bath.

RICHNESS OF THE GAS IN THE CYCLE

We may use either pure propylene or a gaseous mixture containing high proportions of propylene together with other gases which do not react with sulfuric acid or acetic acid, such, for example, as propane, ethane, methane, air, nitrogen, butane, etc. Where such propylene-containing mixtures are fed to the cycle, it is necessary continuously to discard from said cycle an amount of gas corresponding to the amount of non-

absorbable gases introduced. Of course, it is not possible to discard only the non-absorbable gases, so that the discard always contains an amount of propylene. The discarding is controlled so as to maintain sufficient richness of propylene in the cycle. The propylene richness may be as low as 30% of propylene by volume but in order that the absorption capacity per hour of the bath be high, it is recommended to maintain said richness above 50% by volume, for example between 50% and 90% by volume.

The process of this invention may be carried out in the apparatus diagrammatically shown in the attached drawing, forming part of this application. In this drawing, 1 is the reaction vessel or reactor which preferably is a tower into the bottom part of which propylene is introduced through a porous plate 2 or any other means for distributing a gas throughout a liquid. The required temperature is obtained and maintained by means of a heating device 3 which may be a steam jacket, an electrical winding or any other conventional device. Aliphatic acid such as acetic acid from tank 4 is fed to reactor 1 through pipe 5 fitted with a control valve 6. Sulfuric acid is fed through pipe 1A. The mixture of gases and vapors leaving reactor 1 through pipe 7 are introduced into a condenser 8, then, if need be, into a scrubbing column 9 to wash them. Column 9 is fed at its upper part with a suitable washing liquid, more particularly aliphatic acid from tank 4, fed through pipe 10 fitted with a control valve 11. The gases leaving from the top of column 9 are recycled to reactor 1 through pump 12. Residual mixture of propylene and inert gas if any is discarded through pipe 13. Fresh propylene or propylene-containing gas is fed through pipe 14. Regulation of the throughput is effected by means of valve 15 inserted in pipe 13. Discarding of a proportion of the bath may be effected through a pipe 16 which, for the sake of illustration, has been placed at the bottom of reactor 1 in the drawing.

Column 9 may be removed from the apparatus if either condenser 8 is cooled very strongly so that the ester content of the escaping gases is very low, or the non-condensed ester is allowed to remain the gas recycle but such a feature results in diminution of production capacity of the bath.

The liquid from condenser 8 and that from column 9 when such column is employed are collected and treated by conventional distillation processes for separating isopropyl ester therefrom. Recovered aliphatic acid is sent back to tank 4 while isopropyl alcohol and isopropyl oxide which are formed in small amounts may be sent back to the bath where they are converted into isopropyl ester. It is thus possible to produce only isopropyl ester without any by-product.

From the above disclosure it should be understood that an important characteristic of our invention consists in the continuous removal from the bath of the isopropyl ester as it is formed therein. This is done by the propylene containing gas of which only a part reacts while the remainder carries off the ester. This feature makes it possible to operate at a temperature substantially below the boiling point of the reaction mixture and to perform the production and separation of the ester in a one-phase, continuous process.

The following examples will show how our invention may be carried into effect. In these examples propylene and the aliphatic acid are fed into a bath whose equilibrium composition is given. This bath was prepared as follows for Example 1:

Sulfuric acid, water and isopropyl alcohol were introduced into reactor 1. There was then fed into this mixture propylene and acetic acid, same being reacted, so that the contents of isopropyl acetate, isopropyl hydrogen sulfate, acetic acid, sulfuric acid and water reached the equilibrium composition of the bath given in Example 1 below and the bath content was maintained at such

composition. The baths in the other examples were similarly prepared.

Example 1

5 Composition of the bath:

Sulfuric acid, 3.2 kg.
Acetic acid, 5.2 kg.
Isopropyl acetate, 1.3 kg.
Water, 1 kg.

10 Isopropyl hydrogen sulfate, 9.3 kg.

Feed:

16 kg. per hour of 99% acetic acid (of which 7.4 kg. per hour are recycled), and
3.85 cubic meters per hour of 99.4% (by vol.) propylene (through pipe 14).

15 Volume of discarded 93% propylene (pipe 13): 0.33 cubic meter per hour.

The remainder of the gas is propane.

Temperature of the bath: 65° C.

20 Feed rate to bath of the propylene gas: 85 cubic meters per hour.

Pure isopropyl acetate produced: 14.6 kg. per hour.

Thus the yield is substantially 100%.

Example 2

25 Composition of the bath:

Sulfuric acid, 4.6 kg.
Acetic acid, 1.6 kg.
Isopropyl acetate, 1.1 kg.
Water, 1.75 kg.

Isopropyl hydrogen sulfate, 7.7 kg.

Feed:

14 kg. per hour of 99.6% acetic acid (of which 8.6 kg. per hour are recycled), and
2.2 cubic meters per hour of 99% propylene (pipe 14).

30 Volume of discarded 56% propylene (pipe 13): 0.053 cubic meter per hour.

The remainder of the gas is nitrogen.

35 Temperature of the bath: 75° C.

Feed rate to bath of the gas: 55 cubic meters per hour.

Pure isopropyl acetate produced: 9.2 kg. per hour.

Thus the yield is substantially 100%.

40 Our invention is particularly suitable for producing isopropyl acetate but is not limited to such production. In accordance with our invention we may react propylene with aliphatic acids other than acetic, such for example as propionic, butyric and isobutyric acids and the homologues of such acids having 5 to 8 carbon atoms. Formic acid, however, cannot be employed. The conditions of sulfuric acidity, amount of aliphatic acid, temperature, rate of passage of gas, should be adjusted according to the aliphatic acid in use, but should be kept within the limits hereinabove set forth.

Example 3

45 Composition of the bath:

Sulfuric acid, 3.95 kg.
Butyric acid, 2.84 kg.
Isopropyl butyrate, 0.90 kg.
Water, 0.70 kg.

50 Isopropyl hydrogen sulfate, 8.65 kg.

Feed: 7.5 kg. per hour of pure butyric acid (of which 0.9 kg. per hour are recycled), and
1.8 cubic meters per hour of 99.4% propylene (pipe 14).

55 Volume of discarded 46% propylene (pipe 13): 0.02 cubic meter per hour.

The remainder of the gas is ethylene, which is not absorbed under the conditions described.

Temperature of the bath: 80° C.

Feed rate to bath of the gas: 60 cubic meters per hour.

Pure isopropyl butyrate produced: 9.75 kg. per hour.

70 Thus the yield is substantially 100%.

Example 4

Composition of the bath:

Sulfuric acid, 2.96 kg.
 Butyric acid, 2.25 kg.
 Isopropyl butyrate, 1.12 kg.
 Water, 0.95 kg.
 Isopropyl hydrogen sulfate, 9.70 kg.

Feed: 11 kg. per hour of pure butyric acid (of which 3.2 kg. per hour are recycled), and 2.25 cubic meters per hour of 99.8% propylene (pipe 14).

Volume of discarded 93% propylene (pipe 13): 0.064 cubic meter per hour.

The remainder of the gas is propane.

Temperature of the bath: 70° C.

Feed rate to bath of the gas: 70 cubic meters per hour.

Pure isopropyl butyrate produced: 11.5 kg. per hour.

Thus the yield is 99.8%.

Example 5

Composition of the bath:

Sulfuric acid, 3.15 kg.
 Octanoic acid, 1.10 kg.
 Isopropyl octanoate, 0.80 kg.
 Water, 0.95 kg.
 Isopropyl hydrogen sulfate, 9.75 kg.

Feed: 3.06 kg. per hour of 98% octanoic acid (of which 0.06 kg. per hour are recycled), and 0.713 cubic meter per hour of 95% propylene (pipe 14).

Volume of discarded 84% propylene (pipe 13): 0.223 cubic meter per hour.

The remainder of the gas is propane.

Temperature of the bath: 77° C.

Feed rate to bath of the gas: 75 cubic meters per hour.

Pure isopropyl octanoate produced: 3.8 kg. per hour.

Thus the yield is substantially 100%.

The weight of sulfuric acid in each of the above examples is given as H₂SO₄.

What we claim is:

1. A process which comprises continuously feeding acetic acid and propylene into a bath of approximately the following composition:

	Percent by weight
Sulfuric acid	20-30
Acetic acid	5-30
Isopropyl acetate	5-10
Water	0.5-10
Isopropyl hydrogen sulfate	69.5-20

maintaining said bath at a temperature of about 60-80° C., the rate of feed of said propylene being about 2-5 cubic meters per hour of propylene per kg. of said bath, the rate of feed of said acetic acid being sufficient to maintain the bath content thereof within the above-mentioned percentage range, and removing isopropyl acetate from the bath by gas containing propylene at substantially the rate at which the isopropyl acetate is formed in the bath.

2. A process in accordance with claim 1 above, in which the gas and vapors leaving the bath are cooled to condense vaporous constituents and the condensate is treated for recovery of isopropyl acetate therefrom.

3. A process in accordance with claim 2 above, in

which said gas and vapors after cooling and condensation of part of the vapors are washed with acetic acid and the liquid resulting from such washing is mixed with the condensate which contains isopropyl acetate.

5. A process which comprises continuously feeding propylene and a saturated aliphatic acid having 2 to 8 carbon atoms into a bath maintained at about 60-80° C. to produce the corresponding isopropyl ester, said bath having approximately the following composition:

	Percent by weight
Sulfuric acid	20-30
Aliphatic acid	5-30
Isopropyl ester	5-10
Water	0.5-10
Isopropyl hydrogen sulfate	69.5-20

the rate of feed of said aliphatic acid being sufficient to maintain the aliphatic acid content of the bath within the range mentioned above, the rate of feed of propylene being about 2-5 cubic meters per hour per kg. of said bath, and removing the isopropyl ester from the bath by gas containing propylene at substantially the rate at which the isopropyl ester is formed in the bath.

5. A process which comprises continuously feeding butyric acid and propylene into a bath of approximately the following composition:

	Percent by weight
Sulfuric acid	20-30
Butyric acid	5-30
Isopropyl butyrate	5-10
Water	0.5-10
Isopropyl hydrogen sulfate	69.5-20

maintaining said bath at a temperature of about 70-80° C., the rate of feed of said propylene being about 2-5 cubic meters per hour of propylene per kg. of said bath, the rate of feed of said butyric acid being sufficient to maintain the bath content thereof within the above-mentioned percentage range, and removing isopropyl butyrate from the bath by gas containing propylene at substantially the rate at which the isopropyl butyrate is formed in the bath.

6. A process which comprises continuously feeding octanoic acid and propylene into a bath of approximately the following composition:

	Percent by weight
Sulfuric acid	20-30
Octanoic acid	5-30
Isopropyl octanoate	5-10
Water	0.5-10
Isopropyl hydrogen sulfate	69.5-20

maintaining said bath at a temperature of about 70-80° C., the rate of feed of said propylene being about 2-5 cubic meters per hour of propylene per kg. of said bath, the rate of feed of said octanoic acid being sufficient to maintain the bath content thereof within the above-mentioned percentage range, and removing isopropyl octanoate from the bath by gas containing propylene at substantially the rate at which the isopropyl octanoate is formed in the bath.
